UNITED STATES PATENT OFFICE.

FREDERICK W. SCHROEDER, OF LONDON, ENGLAND.

KEY FOR LOCKS.

No. 838,910.

Specification of Letters Patent.

Patented Dec. 18, 1906.

Application filed October 30, 1905. Serial No. 284,983.

To all whom it may concern:

Be it known that I, FREDERICK WILLIAM SCHROEDER, a subject of the King of Great Britain, residing at 9 Arundel street, Strand, London, England, have invented certain new and useful Improvements in Keys for Locks, of which the following is a specification.

This invention relates to locks of the kind which are commonly known as "Yale" locks and to keys for operating the same.

According to the present invention the lever-teeth or serrated edge or edges of such keys are provided with a protective flap or flaps, whereby the working parts are protected from attrition when not in use, and, further, it is rendered difficult to obtain an impression or model of the working parts of the key for purposes of fraud or otherwise.

The invention further involves a simplification of such locks by the reduction of the number of working parts thereof.

The improved lock or key is illustrated in the accompanying drawings, in which—

Figure 1 is a longitudinal section with parts broken away, and Fig. 2 is a transverse section showing the key fitted in the lock and lock-pins withdrawn to enable the barrel to be rotated by the key. Fig. 3 is a side and end elevation of the key. Fig. 4 is a transverse section similar to Fig. 2, but showing the key depressing the lock-pins. Fig. 5 is a transverse section through the barrel between the lock-pins, showing the ward projecting into the key-slot. Fig. 6 is a side elevation in section of one of the locking-pins; and Figs. 7 and 8 are views similar to Figs. 2 and 3, showing a slightly-modified construction.

Mounted to slide transversely in the lock barrel or plug *a*, which is provided with a suitable longitudinal ward or wards *m* for the reception of the key *b*, by which it is rotated, are lock-pins *c*, mounted in channels in said ward, which coöperate each with a corresponding lever or tooth *b'* of the key. These lock-pins or pin-tumblers are urged in one direction by means of springs *d*, which are compressed between the heads *c'* of the lock-pins and collars or projections *d'* in the interior of the lock-barrel to engage in a slot or in holes or recesses *e'* in a fixed casing or sleeve *e*, surrounding the barrel, and are urged in the opposite direction by their hook-shaped lower ends *c''*, encountering the teeth

or levers *b'* of the key as the latter is inserted into its wards in the keyway or path *k*.

The lock-pins or pin-tumblers are preferably bifurcated or **U**-shaped, one of the limbs of the fork—namely, the pin part *c* already described—being arranged to slide in a transverse recess in the lock-barrel *a*, while the other limb *f* of the fork slides in another transverse hole or slot or in a transverse slit *g* in the edge of the barrel. The tails *f''* of the limbs coöperate with a slot or holes *f''* in the fixed sleeve *e*, the arrangement being such that when the key of a given lock has been properly inserted therein the bifurcated lock-pins are retracted by their springs *d*, so as to hold the hooks *c''* in engagement with the corresponding reëntrant serrations of the key *b*, the heads *c'*, and the tails *f''* of the bifurcated lock-pins being then flush with or at any rate not projecting beyond the surface of the barrel *a*, so that the latter may be turned by means of the key and the lock-bolt thereby retracted. When any key differing materially from the proper key is inserted in the wards, then one or more of the heads or tails of the bifurcated lock-pins or the heads of some pins and the tails of others will project into the slots or holes *e' f''* and prevent the rotation of the barrel and the retraction of the lock-bolt.

The projecting flap or hood *b''* of the key may be formed in one piece with the key or may be separately formed and afterward attached to it, the edge of the flap or hood being arranged to overlap the serrated edge of the key and form a shield or guard therefor, as shown in Fig. 2.

It may be convenient, in order to increase the possible range of movement of the lock-pins, to make a slot or groove or holes *h* in the protective hood *b''*, so as to allow the lower ends of the pins *c* to project into or through such grooves or holes as the key is pushed home into its position in the lock, such grooves, slots, or holes corresponding in position with the points of the teeth or of one or more of the teeth of the key.

In the modified construction shown in Figs. 7 and 8 the key *h* is formed substantially **U**-shaped in cross-section and a double set of serrations or levers *b'* on internal shoulders on each limb of the **U**, as shown in Fig. 8. The serrations on each limb are thus protected by the hood or guard constituted by the other limb of the key. The serrations on

the two limbs may of course be varied in number, pitch, and depth in any desired manner. Coöoperating with the double set of serrations b' are two sets of spring-urged lock-pins c' , which are substantially identical with those shown in Figs. 1, 2, and 4 and operate precisely in the manner already described.

This application is a partial division of my prior application, Serial No. 255,401, filed

10 April 13, 1905.

Having described my invention, I claim—

1. A key having a projecting bit, and a hood normally overlapping the outer edge of the bit.
- 15 2. A key having a bit projecting at one side, and a hood carried by the opposite side of the key and normally overlapping the outer edge of the bit.
- 20 3. A key having one edge provided with a projecting bit, the opposite edge of the key being bent to form a hood embracing the outer edge of the bit.
- 25 4. A key having the parts adapted to engage the operative portion of the lock protected by means of an overlapping hood; substantially as described.
5. A key having the parts adapted to engage the operative portion of the lock pro-

tected by means of an overlapping hood, and having an intervening space to receive the 30 ward of the lock; substantially as described.

6. A key for a tumbler-lock, having one side serrated to form the lever edge, and the other side partially inclosing the said lever edge to form a protecting-flap overlapping 35 the entire serrated portion; substantially as described.

7. A key provided at one side with a series of projecting bits, and a hood carried by the key and normally overlapping the outer 40 edges of all of the bits.

8. A key having one edge of its shank provided with a series of projecting bits, the other edge of the shank being bent to form a hood overlapping the outer edges of all of the 45 bits.

9. A key having a projecting bit, and a hood rigidly carried by the key and overlapping the outer edge of the bit.

In testimony whereof I affix my signature 50 in presence of two witnesses.

FREDERICK W. SCHROEDER.
